UNITED STATES PATENT OFFICE.

AUGUST W. JANSSON, OF KENT, OHIO, ASSIGNOR TO THE KENT MACHINE COMPANY,
OF KENT, OHIO, A CORPORATION OF OHIO.

BLANK CARRIER FOR HEADING MACHINES AND THE LIKE.

Application filed February 18, 1920. Serial No. 359,599.

To all whom it may concern:

Be it known that I, AUGUST W. JANSSON, a citizen of the United States, residing at Kent, in the county of Portage and State 5 of Ohio, have invented a certain new and useful Improvement in Blank Carriers for Heading Machines and the like, of which the following is a full, clear, and exact description.

10 This invention relates to a blank carrier employed in connection with heading machines and the like in conjunction with a cutter bar to carry the severed blanks laterally from the point of severance to the dies 15 or other instrumentality which operates on the blanks.

The chief object of the invention is to provide a carrier having a blank holding finger so mounted and operated that the carrier 20 is more positive in action in the respect that it holds the blanks more effectively, permits greater speed, and is quieter in operation than the carriers heretofore employed.

Other and more specific objects are to provide a construction which is easy to assemble and easy to take apart for repairs and the like, easy to keep clean and having less protruding parts than the prior devices, thus eliminating a source of danger to the 30 operator.

The above and other objects are accomplished by my invention which is illustrated in the drawings, described in the specification, and set forth in the appended 35 claims.

In the accompanying sheet of drawings, Fig. 1 is a side elevation with parts in section of the preferred embodiment of my invention, illustrating the carrier mounted 40 on a cutter bar slidably mounted in a portion of the machine which for convenience will be assumed to be a header; Fig. 2 is a bottom plan view of the carrier bar; Fig. 3 is a top plan view of the outer part of the 45 carrier; and Fig. 4 is a diagrammatic or conventional view of a header in connection with which my invention has utility.

In the drawings 10 represents a cutter bar adapted to be slidably mounted in the 50 stationary part of a machine such as a header 11 as illustrated in Fig. 4, and provided at its inner end with a cutter 12 which cuts blanks from a wire or rod 13 (see Fig. 4) fed into the machine, and with the 55 operation of the carrier conveys the blanks

laterally to dies such as upsetting dies 14. The cutter bar is usually provided with a roller 15 (see Fig. 1) which engages in a cam slot of a cam 16 which is reciprocated by suitable parts of the machine to move the 60 cutter laterally inward and laterally outward in harmony with the blank operating parts.

To hold the blanks or sections when cut off from the stock 13 by the cutter, and with the assistance of the cutter to carry them laterally to the dies 14, a so-called carrier is utilized, which in this instance includes a carrier bar 17, which extends over the cutter bar 10, and as here shown, is pivoted at 70 18 to the top of an upstanding arm 19 at the outer end of the cutter bar. Preferably this carrier bar 17 is channel shaped, as shown particularly in Fig. 2, a portion of the channel groove which is on the under side of the 75 bar being narrowed as shown at 20 to cooperate with the tongue of a guide block 21 mounted on the machine as shown in Fig. 1.

Yieldable connecting means is provided 80 between the inner portions of the carrier bar 17 and cutter bar 10 to yieldingly hold the carrier bar down onto the lower part of the guide block 21, but nevertheless to permit the bar 17 to be swung upwardly, and though this connecting means may assume different forms it is preferable in the 85 form of a coil spring 22.

The part of the carrier which holds the blanks to the cutter 12 while they are being carried laterally to the dies consists of a 90 finger 23, preferably in the form of a flat bar mounted so that it may be swung outwardly to release the blank when the latter is held by the dies so that the cutter can be retracted. The manner in which this finger is mounted and spring actuated so as to 95 function in the desired manner forms an important part of the invention. In this instance the upper part of the finger is held by set screws 24 in a slot at the inner end of a finger block 25 whose outer portion is reduced in size to form a tongue 25^a, and extends into a slot at the inner end of the carrier bar 17, in which slot the finger block is pivoted as by means of a cross pin 100 or screw 26.

The finger and finger block are held in 105 normal position with respect to the cutter as shown in Fig. 1, but yieldingly in such position so that the finger and block may 110

swing about the axis of the pivoting pin 26, and in this instance this is accomplished by a plunger 27 which engages the upper part of the tongue 25^a of the block 25, and by a coil spring 28, both the spring and the major portion of the plunger being located in a barrel 29, formed on the upper part of the carrier bar 17, and lying parallel to the body portion of the bar. An adjustable 10 screw 30 at the outer end of the barrel permits the tension of the spring 28 to be adjusted so that the desired pressure is exerted on the block.

It is to be noted that when the cutter bar 15 is being retracted after delivering the blank to the dies, the finger block 25 swings on the axis of the pin 26 a sufficient amount to allow the lower end of the finger to clear the blank. When this takes place the spring 20 28 is compressed slightly, and then when the finger rides over the blank, the block and finger are immediately restored to normal position with respect to the cutter. It is to be noted also that when the block 25 swings from normal position the point or end of the plunger rides over the inner face of the tongue of the finger block, increasing the leverage through which the spring 28 acts, and thus increases the effectiveness 30 of the spring without requiring any considerable movement of the spring. These are features which contribute to the efficiency and durability of the carrier.

With the carrier above described, the objects stated in the early part of the specification are attained to a very high degree, but nevertheless certain features may be modified in construction without materially, if at all, decreasing the effectiveness of the 40 device as a whole, and I aim to include all such modifications which fall within the scope of the appended claims.

Having described my invention, I claim:

1. In combination with a cutter and cutter bar, of a header and the like, of a carrier co-operating with the cutter to hold blanks comprising a finger normally supported adjacent the cutter, a pivoted member supporting the finger, a support for said pivoted member, and means extending lengthwise of said support and acting on said pivoted member to yieldingly resist its movement in one direction.

2. A carrier for use in connection with a reciprocating cutter and cutter bar comprising a carrier bar adapted to be supported on the cutter bar, a finger block pivotally supported on the carrier bar, a carrier finger supported by said block and a device yieldable in a direction lengthwise of the carrier

bar and yieldingly resisting the movement of the block in one direction.

3. In combination with a cutter and cutter bar of headers and the like, of a carrier comprising a carrier bar connected to the cutter bar, a finger block having a carrier finger and pivotally connected to the carrier bar, and means yieldingly resisting the movement of the finger block and acting on the same through a leverage which increases as the finger swings away from the cutter.

4. In combination with a reciprocating cutter and cutter bar, of a carrier co-operating therewith and comprising a carrier bar connected to the cutter bar, a finger block movably connected to the carrier bar, a carrier finger supported by the block, and a spring pressed plunger on the carrier bar and movable in a direction parallel therewith, said plunger engaging said finger block and yieldingly resisting its movement.

5. The combination with a reciprocating cutter and cutter bar of a carrier comprising a carrier bar pivotally connected at its outer end to the cutter bar, a finger block pivotally connected to the inner end of the carrier bar and having a carrier finger normally adjacent the cutter, a barrel carried by the carrier bar, and a spring pressed plunger in the barrel and engaging the finger block to yieldingly resist pivotal movement thereof.

6. In combination with a reciprocating cutter and cutter bar of a blank carrier comprising a carrier bar connected to the cutter bar so as to reciprocate therewith, a finger block carrying a finger normally adjacent the cutter and having a tongue pivotally connected to the carrier bar, and means engaging a portion of the tongue to yieldingly resist pivotal movement of the finger block on the carrier bar.

7. In a metal working machine, a laterally reciprocating cutter and cutter bar for severing stock into sections, a carrier for said cutter bar comprising a carrier bar connected to the cutter bar, yieldable means for holding the carrier bar normally in predetermined position with respect to the cutter bar, a finger block pivotally connected to the carrier bar and having a finger with a portion normally adjacent the cutter, and a spring pressed plunger carried by said carrier bar and engaging a portion of said finger block to yieldingly resist its pivotal movement on the carrier bar.

In testimony whereof, I hereunto affix my signature.

AUGUST W. JANSSON.
